UNITED STATES PATENT OFFICE.

AMBROSE RYDER, OF CARMEL, NEW YORK.

UMBRELLA, PARASOL, AND THE LIKE.

Application filed August 7, 1926. Serial No. 127,845.

This invention relates to improvements in umbrellas, parasols and the like and the principal object of the invention is the provision of what I term an "off-center" device 5 in which the shaft, stick or rod instead of extending vertically and centrally of the frame and cover as a whole, extends at an angle thereto and in a position relatively adjacent to the inside of the cover and frame 10 whereby the person using the umbrella, parasol and the like is fully protected, the head, shoulders, arms and a large portion of the body or trunk being directly covered by the umbrella when in use.

15 A further object of this invention is the provision of such a device which is very strongly constructed and capable of withstanding ordinary and in fact extraordinary usage.

20 Another object is the construction of such a device which is composed almost entirely of standard parts and of standard construction, in other words the embodiment of my invention necessitates the use of a minimum 25 number of new elements of construction.

30 A further object of the invention is the provision of such a device having a plurality of spreaders or stretchers for the ribs of the frame and an operating member having a connection with a rib and an intermediate 35 connection with the spreaders or stretchers and adapted to be positioned at different places on the stick, shaft or rod to hold the spreaders or stretchers spread or closed, the stick, shaft or rod being off-center when the device is opened.

To the accomplishment of the foregoing and such other objects as may hereinafter appear, this invention consists in the construction, combination and arrangement of parts hereinafter described and then sought 40 to be defined in the appended claims, reference being had to the accompanying drawings forming a part hereof and which show, 45 merely for the purpose of illustrative disclosure, a preferred embodiment of my invention, it being expressly understood, however, that various changes may be made in practice within the scope of the claims without digressing from my inventive idea.

In the drawings—

50 Figure 1 is a side elevation of an umbrella frame and cover embodying my invention, parts being shown in section to facilitate the disclosure, this being an open or extended position.

Figure 2 is a view similar to Figure 1 on an enlarged scale except that the device is in closed position.

Figure 3 is a bottom plan view of the 60 inner ends of the spreaders or stretchers and the element which connects them and the operating means for raising and lowering them.

Figure 4 is a view similar to Figure 3 65 showing a modified form of construction.

Referring now to the drawings, the numeral 1 designates a standard frame for an umbrella, parasol and the like. It is composed of a plurality of ribs 2, which may be 70 pivotally connected at their upper ends at the center of the device to a notched disc 3, or "notch," as it is called, preferably by the usual method of wiring the ends of the ribs by means of eyes formed therein to a peripheral groove formed in the notch.

75 Spreaders or stretchers 4 are preferably pivotally connected at their outer ends to the ribs as at 5 and at their inner ends are 80 preferably pivotally connected to the lower 85 notched disc 6, this pivotal connection, in the form shown, being the standard form of connection, as previously described. It is to be understood that various other connections may be utilized. This connection includes the wire 7 passing through the eyes 8 in the ends of the spreaders or stretchers and located in the annular groove 9 formed in the edge of the disc 6. The ends of the spreaders or stretchers themselves fit within 90 the notches 10 of the disc 6. Therefore, when the disc is raised the spreaders or stretchers are forced outwardly to open and spread the frame and cover and when the disc 6 is moved downwardly the spreaders 95 or stretchers are withdrawn to close the frame and cover.

The stick, shaft, or rod 11 is mounted in the upper notched disc 3 in such a manner that it may be extended in an off-center position relative to the frame and cover as a whole. By that is meant in a position at an angle to the true central vertical position which the stick usually assumes in the standard umbrella when open. A sleeve or 100 runner 12 is mounted to move or slide on the stick 11, being provided with the slot 13 to receive the lowermost catch 14 on the stick when the umbrella or the like is closed, which is also provided with an upper catch 105 15 over which the sleeve or runner 12 passes when the umbrella or the like is opened, so

that it engages the lower end thereof in accordance with standard umbrella and parasol practice. This sleeve or runner 12 is preferably provided with the laterally extending lug 16 which is provided with a slot 17 to form two ears 18 which are apertured to receive a pin 19, which forms a pivotal connection for the free end of rod or strut 20. This rod or strut is the operating member for the device whereby it is opened or closed. It is provided intermediate its ends with the eye or eyes 21 whereby it is pivotally connected to one of the notches of the lower notched disc 6. The other end of this rod or strut 20 is preferably pivotally connected to one of the ribs 2. In fact, this rod or strut 20 takes the place of one of the spreaders or stretchers 5, so that it may be said to be one of the spreaders or stretchers 5 having its end portion extended beyond the connection of the spreader or stretcher to the lower notched disc 6 to connect with the sliding sleeve or runner 12. This rod or strut 20 may be bent or formed so that when in its uppermost raised position it will engage the under surface of the notched disc 6 for substantially the full width of the disc and thereby support the same.

It is seen that when the sliding sleeve or runner 12 is moved upwardly the lower notched disc 6 will be forced away from the stick due to the fixed pivotal connections between the notched disc 6 and the rod or strut 20, on the one hand, and the sleeve or runner 12 and the rod or strut 20, on the other hand. Furthermore, the notched disc will not only be forced away from the stick but will also be forced upwardly toward the upper notched disc 3 and force the spreaders or stretchers outwardly to open and expand the frame and cover. When the sleeve or runner 12 is moved downwardly the movement of these parts is reversed and the notched disc 6 moves downwardly and toward the shaft or stick until the frame and cover are closed due to the fact that the ribs are drawn closely to the stick or shaft. The lower notched disc 6 is preferably provided with one or more extra notches 10 in addition to those necessary for the mounting and connection of the inner ends of the spreaders or stretchers 4 and this extra notch or notches are positioned at the point where the stick or shaft 55 approaches the notched disc 6 when in closed position. This permits a complete closing action without the necessity of subjecting any of the parts to undue tension.

Various constructions may be utilized to permit the positioning of the stick or shaft off-center relative to the frame when open. The standard connection between the ribs, notch and the stick may be sufficient or it may be advisable to form a pivotal connection in the upper end portion of the stick or

shaft. This may be accomplished by the hinged or pivoted joint 22, as illustrated, or in various other ways.

It is to be noted that the handle 23 for the stick may be so positioned or of sufficient length that it extends well up within the frame and cover when the same is closed, and that when open and in use the hand and arm of the user or the umbrella will be covered and protected thereby.

In the modification, illustrated in Fig. 4 of the drawing, the strut or rod 20' is provided with an opening 24 to which the inner ends of the spreaders or stretchers 4 are connected without the use of any element corresponding to disc 6. The spreaders or stretchers are directly connected to the strut or rod. Furthermore, the sleeve or runner 12 may be dispensed with and the end of the strut or rod may have an adjustable connection at different positions on the stick.

As stated, this construction is simple and strong and practically all the elements thereof, as well as the construction itself, is standard, very few extra parts being required.

In other forms the spreaders or stretchers may be of different or varying lengths and the strut or rod be shorter than some or all of them.

What I claim is:

1. In combination, in an umbrella, parasol, or the like, a frame including ribs and spreaders connected thereto, a stick pivotally connected at the upper end to the frame to swing from a central to an off-center position without straining or distorting the said frame, an operating member connected at one end to a rib, said spreaders having an operative connection with said member intermediate its ends, and the other end of said member being adapted to be adjustably positioned in connection with said stick to raise and lower said frame.

2. In combination, in an umbrella, parasol, or the like, a frame including ribs and spreaders connected thereto, a stick pivotally connected at the upper end to the frame to swing from a central to an off-center position without straining or distorting the said frame, an operating member connected at one end to a rib, said spreaders having an operative connection with said member intermediate its ends, the other end of said member being adapted to be adjustably connected to said stick in at least two positions to hold said frame in raised or lowered position.

3. In combination in an umbrella, parasol or the like, a frame including a plurality of ribs, a stick to which the ribs are connected at their upper ends, said stick having a pivotal connection at its upper end to the frame to permit it to swing from a central position to an off-center position without

distorting or straining the frame; a plurality of spreaders, the ends of which are connected to the ribs, an element to which the inner ends of the spreaders are connected, a runner 5 slidably mounted on the stick, and a strut connected at one end to one rib and connected at its other end to said runner and having an intermediate connection to said element.

4. In combination, in an umbrella, par-
10 sol or the like, a frame including a plurality of ribs, a stick to which the ribs are connected at their upper ends, said stick having a pivotal connection at its upper end to the frame to permit it to swing from a central
15 position to an off-center position without distorting or straining the frame; a plurality of spreaders, the ends of which are connected to the ribs, an element to which the inner ends of the spreaders are connected, a runner 20 slidably mounted on the stick, and a strut connected at one end to one rib and connected at its other end to said runner and having an intermediate connection to said element, said strut being of greater length than
25 said spreaders.

5. In combination, in an umbrella, para-
sol or the like, a plurality of ribs, a stick to which the ribs are connected at their upper ends, a plurality of spreaders, the ends of
30 which are connected to the ribs, a strut connected at one end to one rib and connected intermediate of its ends to the inner ends of said spreaders, and a runner slidably mounted on the stick and connected to the
35 inner end of the said strut.

6. In combination, in an umbrella, para-
sol or the like, a plurality of ribs, a stick to which the ribs are connected at their upper ends, a plurality of spreaders, the ends of
40 which are connected to the ribs, a strut connected at one end to one rib and connected intermediate of its ends to the inner ends of said spreaders, and means for adjustably connecting the inner end of the said strut
45 to the stick for holding the frame in raised or lowered position.

7. In combination, in an umbrella, para-
sol or the like, a plurality of ribs, a stick to which the ribs are connected at their upper ends, a plurality of spreaders, the ends of
50 which are connected to the ribs, a strut connected at one end to one rib and connected intermediate of its ends to the inner ends of the spreaders, and a runner slidably mounted on the stick and connected to the inner
55 end of the strut, whereby when the spreaders are forced upwardly the stick is held in an off-center position relative to said frame.

8. In combination, in an umbrella, para-
sol or the like, a plurality of ribs, a stick to
60 which the ribs are connected at their upper ends, a plurality of spreaders, the ends of
65 which are connected to the ribs, a strut connected at one end to one rib and connected intermediate of its ends to the inner ends
70 of the spreaders, and means for adjustably connecting the inner end of the strut to the stick to hold the said frame in raised or lowered position, said means also operating to hold the stick in off-center position relative to the frame when the latter is raised.

9. In combination, in an umbrella, para-
sol or the like, an upper notched member,
75 ribs connected at their upper ends to the
said member, spreaders connected at their
outer ends to the ribs, a lower notched mem-
ber to which the inner ends of the ribs are
80 connected, a stick arranged at one side of
the lower notched member and pivoted at its
upper end to the upper notched member to
swing from a central position to an off-cen-
85 ter position without straining or distorting
the frame, a strut pivoted at its outer end
to one of the ribs and intermediate of its
notches of the lower
90 notched member, and a runner slidably on
the stick and connected with the inner end
of the strut.

In testimony that I claim the foregoing,
I have hereunto set my hand this 6th day
of August, 1926.

AMBROSE RYDER.
